UNITED STATES PATENT OFFICE.

ARNALDO MARZIO, OF MILAN, ITALY.

PROCESS OF MECHANICAL RELIEFING PREVIOUS TO TYPOGRAPHIC PRINTING.

1,233,799.

Specification of Letters Patent.

Patented July 17, 1917.

No Drawing

Application filed March 20, 1916. Serial No. 85,489. (Specimens.)

To all whom it may concern:

Be it known that I, ARNALDO MARZIO, a subject of the King of Italy, residing at Milan, Kingdom of Italy, have invented 5 certain new and useful Improvements in Processes of Mechanical Relieving Previous to Typographic Printing, of which the following is a specification.

To prepare for printing off, it is usual to 10 place on the surface of the cylinder which is to receive the sheet of paper to be printed through pressure against an inked form, a number of reliefs which force the paper to project in such places where a very black 15 print is desired. Such reliefs have to raise the paper more or less according to the greater or smaller effect which is desired at a given point. It is usual to proceed in this matter by pasting bits of paper on a 20 sheet previously printed from the form so as to obtain graduated reliefs in different points according to the effects desired. Such an operation requires a long time and a special ability and is therefore expensive.

25 Many ways have been devised to dispense with the work ordinarily involved by using special substances to form reliefs at given points—but no successful system has been introduced, as such substances demand 30 dampness or heat to become adherent to the sheet, the consequence being an alteration in the dimensions of the sheet which destroys the correspondence between sheet and form and leads to indifferent results. The process which is to be described here is based upon the use of a resinous granular matter, 35 in grains of convenient size, free of dust.

Just after obtaining a print from the 40 form on the sheet, which ought to be thin, absolutely non absorbent and preferably transparent, this print is covered with the resinous grains. The viscous ink fixes an amount of the grains proportional everywhere to the density of the ink, and therefore proportional to the desired relief.

45 After taking off the surplus grains with a brush or any other convenient tool, a brush is used to cover the sheet with powdered pumice stone or other fine and inert 50 powder of any kind to give consistence to and protect the grains, after which the sheet

is passed through a calender, or the printing machine itself is used for that purpose, the object being to promote the perfect amalgamation of the pumice stone with the 55 resinous powder.

If necessary both faces of the sheet may be treated in the manner above described or several sheets may be treated so as to obtain such reliefs as found desirable.

60 Claims:

1. A process of typographic relieving, which consists in obtaining an impression from the inked form upon a foundation sheet; dusting the printed surface of the 55 sheet with a resinous powder, so as to cause the ink to fix said powder throughout the impression proportionally to the density of the ink thereon; and applying an inert powder to the surface so treated, to give 70 consistence to the resinous powder and to protect the same.

2. A process of typographic relieving, which consists in obtaining an impression from the inked form on a thin, non-absorbent, transparent sheet; dusting the printed 75 surface of the sheet with a resinous powder, so as to cause the ink to fix said powder throughout the impression proportionally to the density of the ink thereon; and applying an inert powder to the surface so treated, to give 80 consistence to the resinous powder and to protect the same.

3. A process of typographic relieving, which consists in obtaining an impression 85 from the inked form upon a foundation sheet; dusting the printed surface of the sheet with a resinous powder, so as to cause the ink to fix said powder throughout the impression proportionally to the density 90 of the ink thereon; applying powdered pumice stone to the surface so treated, to give consistence to the resinous powder and to protect the same; and finally amalgamating the inert powder with the resinous powder 95 by pressure.

In testimony whereof I hereby affix my signature this 22nd day of February, 1916.

ARNALDO MARZIO.
